- (57) **CLAIM**
The ornamental design for an ultrasound probe, as shown and described.

DESCRIPTION

FIG. 1 is a perspective view of an ultrasound probe according to Embodiment 1,
FIG. 2 is a front view of the ultrasound probe,
FIG. 3 is a back view of the ultrasound probe,
FIG. 4 is a plan view of the ultrasound probe,
FIG. 5 is a bottom view of the ultrasound probe,
FIG. 6 is a right side view of the ultrasound probe; and,
FIG. 7 is a left side view of the ultrasound probe.
The dashed lines in the drawings depict portions of the ultrasound probe that form no part of the claimed design. The dot-dash dot broken lines depict the boundaries of the claim and form no part thereof.

1 Claim, 3 Drawing Sheets
